UNITED STATES PATENT OFFICE

2,483,258

SMOKING PIPE

Frank Grosse Borger, Fort Lee, N. J., assignor to
Wilhelm Fischer, Fort Lee, N. J.

Application April 17, 1945, Serial No. 588,861

1 Claim. (Cl. 131—216)

1 This invention relates to smoking pipes and has for an object to provide a pipe which will produce a "dry smoke."

Another object of the invention is to provide in a smoking pipe, means whereby the smoke will be properly cooled before reaching the mouth of its user.

A further object of the invention is to provide a smoking pipe, the smoke passage through the stem of which gradually increases in diameter from the bowl to the mouthpiece thereof.

Other features and advantages will become more readily apparent from the following description and the accompanying illustrative drawing in which:

The figure is a longitudinal sectional elevational view of my improved pipe.

Same reference characters indicate same parts in the drawing and specification, and **10** indicates one form of the invention.

In the figure, **12** indicates a smoking pipe bowl having a stem section **13**, the smoke channel **14**, of which tapers in diameter from the comparatively very small port **15** at one side of the bottom of the bowl, to the end **16** of member **13**. To said end **13** is connected a detachable stem or mouthpiece section **17**, having a tapering passage **18**, the diameter of which at its juncture **19** with the smoke channel **14** is the same as the outer terminal diameter **20** of said smoke channel in section **13**, and which gradually increases in diameter to its outlet **25** at the outer extremity of the mouthpiece **17**.

It will thus be observed that the smoking pipe embodying the invention has a straight-walled smoke passage which gradually and continuously increases in diameter or cross-sectional area from a small opening in one side of the bowl adjacent the bottom thereof to the outer extremity of the mouthpiece, whereby free and rapid movement of smoke and moisture from the bowl to the outlet **25** of the mouthpiece is insured and settling down or condensation of moisture in the smoke passage is prevented.

I have proved through my comparative experi-

2 ments with the above described pipe and those having straight bores through the pipe stem that I have invented a smoking pipe which gives a dryer, cooler and in every way a more pleasant smoke than those of the usual construction.

It is thought that persons skilled in the art to which the invention relates will be able to obtain a clear understanding of the invention after considering the description in connection with the drawing. Therefore, a more lengthy description is regarded as unnecessary.

Minor changes in shape, size and rearrangement of details and parts such as come within the purview of the invention claimed may be resorted to, in actual practice, if desired.

Having now described my invention that which I claim as new and desire to procure by Letters Patent is:

A smoking pipe comprising a bowl, a stem and **20** a mouthpiece, said stem and mouthpiece comprising a smoke passage starting at the tobacco holding cavity of the bowl adjacent the bottom thereof and terminating at the free end of the mouthpiece; said passage in entirety being uniformly tapered in at least one longitudinal section from a small cross-sectional area at the bowl end to a larger cross-sectional area at the free end of the mouthpiece.

FRANK GROSSE BORGER.
